Application October 19, 1948, Serial No. 55,340

8 Claims. (Cl. 321—27)

1

This invention relates to rectifying apparatus and particularly to a rectifier comprising two grid-controlled gaseous discharge devices operating in parallel.

The principal object of the invention is to provide means for initiating conduction at effectively the same instant in two grid-controlled gaseous discharge devices operating in parallel.

A further object of the invention is to provide a new and improved control system for two grid-controlled gaseous discharge devices operating in parallel whereby the currents in the two devices, respectively, are maintained substantially equal.

A characteristic of a grid-controlled gaseous discharge tube is that, in order to start conduction between the anode and cathode, it is necessary to first form an arc discharge between the control grid and the cathode. The grid voltage required for this depends upon the anode voltage and upon the design of the tube. When conduction starts, the grid thereafter loses control until the flow of current between anode and cathode is interrupted, after which it regains control until another breakdown occurs between grid and cathode.

For the successful operation of two such tubes in parallel, for greater rectified output, it is desirable that the tubes become conducting at practically the same instant in the cycle of the supply voltage, and that during the conducting portion of the cycle the current remain substantially equal in two tubes. Assuming the first condition to be satisfied, the latter requirement can be met by means of a center-tapped equalizer coil with one-half of its winding connected in series with one of the tubes and the other half in series with the other tube. Since considerable variation in the critical grid firing voltage is common between tubes of the same type, it is preferable that the voltage applied to the grids of the tubes have a very steep wave front in order to raise the grid-cathode voltages of the two tubes, respectively, above the critical firing voltage at the same time. If a circuit for producing an abruptly rising peaking voltage were used for this purpose, the load capacity of the circuit would, of course, need to be double that required for a single tube.

The requirement of a special peaking circuit for both tubes is obviated by the use of my invention, wherein the equalizer coil above mentioned is provided with an auxiliary winding placed in inductive relation to the original winding and connected in the grid-cathode circuit of one of the rectifier tubes, which may be termed the controlled tube. Upon the grid-cathode circuit of

2

the other tube, that is, the controlling tube, there is impressed a firing voltage which need not be peaked but which may be a voltage obtained from an alternating-current supply source. When the controlling tube is fired and space current begins to flow therein, a voltage is thereby induced in the auxiliary winding which immediately fires the controlled tube. Throughout the rest of the cycle the current is maintained equally divided between the tubes by the well-known action of the equalizer coil.

Under certain circumstances, as hereinafter explained, the auxiliary coil may be dispensed with and the above results obtained by means of the equalizer coil.

The invention is applicable to the operation of two grid-controlled gaseous discharge tubes connected in parallel as a half-wave rectifier, or two pairs of such tubes connected as a full-wave rectifier.

The invention will be more clearly understood from the following detailed description and the accompanying drawing, of which:

Fig. 1 is a schematic view of a half-wave rectifier embodying the invention;

Fig. 2 is a modification of the circuit of Fig. 1; and

Fig. 3 is a schematic view of a full-wave rectifier embodying the invention.

Referring to Fig. 1, the grid-controlled gaseous discharge tubes 1 and 2 are connected in parallel to form a half-wave rectifier for supplying rectified current from an alternating-current source 3 to a load 4. The primary of a transformer 5 is connected to the alternating-current source 3 and its secondary is connected between one side of the load 4 and the midpoint of an equalizer coil 6. The end terminals of the equalizer coil are connected respectively to the anodes of tubes 1 and 2. The cathodes of the tubes are connected in parallel across the center-tapped secondary 7 of a heater transformer, the primary of which is omitted from the drawing. The midpoint of the secondary 7 is connected to the other side of the load 4.

The grids of tubes 1 and 2 are provided with a negative bias from a potentiometer 8 connected in parallel with a condenser 9 across the output terminals of a bridge rectifier 10, to which alternating current is supplied from source 3. A firing voltage for tube 1 is supplied by a transformer 11, the primary of which is connected to source 3 and the secondary of which is connected between the grid and cathode of this tube in series with a portion of the biasing potentiometer 8.

and resistor 12. An auxiliary winding 13 in inductive relation to equalizer coil 6 is provided in a circuit connecting the grid and cathode of tube 2, there being included in said circuit a resistor 14 and a portion of the voltage across potentiometer 8. Winding 13 is so poled as to supply a positive potential to the grid with respect to the cathode. It will be apparent that the combination of equalizer coil 6 and auxiliary winding 13 is, in effect, a transformer having a center-tapped primary.

When at the beginning of a half cycle of the source 3, the secondary of transformer 5 is applying an increasing positive voltage to the anodes of tubes 1 and 2, at the same time the secondary of transformer 11 is applying a positive voltage to the grid of tube 1. When the latter voltage has sufficiently overcome the negative bias provided by rectifier 10, tube 1 ionizes and becomes conducting, its grid-cathode current being limited by resistor 12. Current then flows through the upper half of the equalizer coil 6, through the anode-cathode space of tube 1, and through the load 4 back to the secondary of transformer 5. The initiation of current through the upper half of coil 6 induces a high voltage in the auxiliary winding 13 which is applied to the grid of tube 2. The auxiliary winding is so designed that this induced voltage is great enough to assure the firing of tube 2, excessive grid-cathode current being prevented by resistor 14. Current will then flow through the lower half of the equalizer coil 6, through the anode-cathode space of tube 2, and through the load 4 back to the secondary of transformer 5. Thus conduction is started in tube 2 at practically the same instant that conduction is initiated in tube 1. Thereafter, during the remainder of the cycle of the alternating-current source, the current will divide equally between the two tubes, or nearly so, due to the balancing action of the equalizer coil 6. For instance, if the current in tube 1 should tend to increase more rapidly than the current in tube 2, the choking action of the upper half of the coil 6 would tend to retard the increase in tube 1, while at the same time a voltage would be induced in the lower half of coil 6 which would tend to increase the current through tube 2. In this manner the reciprocal action tends to maintain the two currents approximately equal.

In the operation of the above circuit it is necessary to adjust the negative bias provided by potentiometer 8 to a value that will always prevent the firing of tube 2 until the start of current in tube 1.

In Fig. 2 there is shown a modification of the circuit of Fig. 1 wherein the equalizer coil is connected on the cathode side of the tubes instead of on the anode side. Like characters are used to designate the same elements in these figures. As in Fig. 1, alternating-current source 3 supplies power to transformer 5, one end of the secondary being connected to one side of the load 4 and the other end to the anodes of tubes 1 and 2. In this case the cathodes are separately heated by the center-tapped secondary windings 15 and 16 of a heater transformer, the primary of which is not shown. The midpoint of secondary 15 is connected to one terminal of the equalizer coil 6 and the midpoint of secondary 16 is connected to the other terminal, the midpoint of the equalizer coil being connected to the other side of the load. A negative grid bias is supplied to each tube by auxiliary rectifier 10 and potentiometer 8 as in Fig. 1, and a firing voltage for tube 1

is supplied by transformer 11. Switch 17 in one position connects coil 13 in the grid-cathode circuit of tube 2 and in the other position it excludes the coil.

With switch 17 in the down position as shown, this circuit operates in the same manner as that of Fig. 1, but has an advantage over the former in the following respect. When, in Fig. 2, current begins to flow through tube 1 and through the upper half of equalizer coil 6, a voltage is thereby induced in the lower half of the coil which makes the cathode of tube 2 more negative with respect to its grid. This voltage therefore aids in the firing of tube 2. If its magnitude were great enough the auxiliary winding could be omitted entirely. This may be accomplished by operating switch 17 to the up position, the grid of tube 2 then being connected directly to the negative terminal of the bias supply.

Fig. 3 illustrates an application of the invention to a full-wave rectifier, in which two tubes of a type such as shown in Figs. 1 and 2 are operated in parallel to rectify one half of the wave and a similar pair of tubes to rectify the other half. In this figure tubes 24 and 25 are connected as a full-wave rectifier to supply direct current to a load 29, and would so operate with tubes 24' and 25' removed from their sockets. With the two latter tubes in position, however, the firing of tube 24 on one half cycle causes tube 24' to fire, these two tubes sharing the load current in parallel. When tube 25 begins to conduct, on the next half cycle, it causes tube 25' to conduct and these two tubes divide the load during this half cycle. Tubes 24 and 25 act therefore as controlling tubes, while tubes 24' and 25' are the controlled tubes.

Referring first to the upper half of Fig. 3, the primary winding of transformer 20 is connected to the alternating-current source 21. The secondary is divided into two parts, winding 22 and winding 23. The upper terminal of winding 22 is connected to the anode of tube 24 and the lower terminal of winding 23 to the anode of tube 25. The other terminals of the two secondary windings are joined together through the upper half of an equalizer coil 26, a conductor 27, and the lower half of an equalizer coil 26'. Conductor 27 is connected through a choke coil 28 to one side of a load 29. The cathodes of tubes 24 and 25 are connected in parallel across the center-tapped secondary 30 of a heating transformer, the primary of which is not shown, and the center tap is connected to the other side of the load 29. A condenser 31 is connected across the output terminals of the rectifier, forming a smoothing filter in combination with choke coil 28. The grids of tubes 24 and 25 are connected respectively to the terminals of the center-tapped secondary of a transformer 32, the midpoint of the transformer winding being returned through switch 33 to the cathodes via the center tap of the secondary winding 30. Current limiting resistors 34 and 35 are connected respectively in the grid-cathode circuits of tubes 24 and 25.

Potentiometer 36 in series with resistor 37, which is shunted by a voltage regulating gas tube 38 and a condenser 39, are connected across the output terminals of the rectifier. Potentiometers 40 and 41 and condenser 42 are connected in parallel across the output terminals of an auxiliary bridge rectifier 43, which is supplied with alternating current from source 21. When switch 33 is in the "on" position it connects the midpoint of the secondary of transformer 32 to the slider of

potentiometer 36, and when in the "off" position to the slider of potentiometer 41.

It will be seen that the portion of Fig. 3 just described constitutes an ordinary full-wave rectifier, employing a single grid-controlled gaseous discharge tube for each half cycle of the alternating current to be rectified. In the lower half of the figure, with exceptions to be noted, tubes 24' and 25' are connected as a similar full-wave rectifier, with its output terminals in parallel with those of the first rectifier. For convenience, the corresponding elements in this half of the drawing are given the same reference numbers as those in the upper half, but with the addition of primes to distinguish them. Here the lower terminal of secondary winding 22' is joined to the upper terminal of winding 23' through the lower half of equalizer coil 26, conductor 27, and the upper half of coil 26'. The grid of tube 24' is connected to one end of the auxiliary winding 44, which is in inductive relation to equalizer coil 26, and similarly the grid of tube 25' is connected to one end of the auxiliary winding 44', which is in inductive relation to coil 26'. The other terminals of the auxiliary windings 44 and 44' are connected together and to the slider of potentiometer 40. The cathodes of tubes 24' and 25' are connected in parallel with those of tubes 24 and 25.

For the protection of gaseous rectifier tubes of this kind it is generally desirable to delay conduction after the application of anode voltage until the cathodes have become heated to the operating temperature. For this purpose switch 33 is provided, which enables the normal operating negative grid bias for the control tubes 24 and 25 to be obtained from potentiometer 36 during operation, or a higher negative bias from potentiometer 41 during the warm-up period. In the operation of this circuit, therefore, switch 33 is turned to the "off" position at the start, with the slider of potentiometer 41 adjusted for a negative bias sufficient to prevent conduction by these tubes due to the anode voltage from transformer 20, and with the slider of potentiometer 40 likewise adjusted for non-operation of tubes 24' and 25'. When the switch is turned to the "on" position after the warm-up period, tube 24 will fire near the start of a half cycle of positive voltage on its anode and grid, and current will begin to flow through its anode-cathode space, through the load 29, through the upper half of equalizer coil 26, and thence back to the secondary winding 22. The voltage thereby induced in the auxiliary winding 44 will cause tube 24' to begin conducting also, the path of this current being from secondary winding 22' through the anode-cathode space of the tube, through the load 29, through the lower half of equalizer coil 26, and thence back to the secondary, and through the rest of the half cycle tubes 24 and 24' will operate in parallel and share the load equally through the action of equalizer coil 26, as previously explained for Figs. 1 and 2.

In the same manner, near the beginning of the next half cycle the controlling tube 25 will start conducting and current will flow through its anode-cathode space, through the load 29, through the lower half of equalizer coil 26', and thence back to the secondary winding 23. The voltage thereby induced in the auxiliary winding 44' will cause tube 25' to fire immediately afterwards, and current will start flowing through its anode-cathode space, through the load 29, through conductor 27, and through the upper

half of equalizer coil 26' back to the secondary winding 23'. Equalizer coil 26' will then act to maintain equality of the currents in tubes 25 and 25' through the rest of this half cycle, in the manner previously explained.

In the adjustment of the biasing potentiometer 36 it is necessary to make sure that the negative bias is sufficient to prevent either controlled tube from firing ahead of its controlling tube. This bias will then be satisfactory for the warm-up period also, i. e., with switch 33 in the "off" position.

When the circuit is operating with switch 33 in the "on" position, the negative bias for the controlling tubes 24 and 25 provided by potentiometer 36 fluctuates with the output voltage, thus varying the instant of firing. This exercises a regulating effect on the voltage, tending to keep it constant. The purpose of the constant voltage discharge tube 38 connected across resistor 37 is to concentrate the entire variation in output voltage across potentiometer 36.

In Figs. 1 and 2, for simplicity, the provision of a separate biasing voltage for the warm-up period is omitted, and likewise the voltage regulating feature just mentioned.

What is claimed is:

1. In combination, a first and a second gaseous discharge device each having an anode, a cathode and a control electrode, a center-tapped reactance coil, means for supplying current from an alternating-current supply source to a load through a circuit having two parallel branch paths, each including the space current path of one of said devices in series with one half of said reactance coil, an auxiliary coil in inductive relation to said reactance coil, a circuit including said auxiliary coil connecting the control electrode and cathode of said second device, and means for impressing upon the control electrode of said first device a potential with respect to its cathode for causing the control of space current in both of said devices.

2. In combination with a rectifier comprising a first and second gaseous discharge device, each having an anode, a cathode and a control electrode, said devices being connected in parallel paths which are in series with an alternating-current source and a load, a control system for insuring substantially equal division of current in said devices comprising a center-tapped equalizer coil the two halves of which are connected respectively in series with the anode-cathode discharge paths of said devices, an auxiliary coil in inductive relation to said equalizer coil, a circuit including said auxiliary coil connecting the control electrode and cathode of said second device, and means for impressing upon the control electrode of said first device a potential with respect to its cathode for initiating conduction therein and thereby initiating conduction immediately afterwards in said second device.

3. In a rectifying circuit having two parallel branch paths through which currents are transmitted from an alternating-current source to a load, said paths respectively comprising a first and a second gaseous space current rectifying device each having an anode, a cathode and a control electrode, means for controlling the current supplied from said source to said load comprising an inductance device having a first and a second winding, means for connecting respectively different portions of said first winding in the said parallel branch paths, a circuit connecting the control electrode and cathode of said

second rectifying device including said second winding, and a circuit connecting the control electrode and cathode of said first rectifying device including a source of voltage for causing conduction to be initiated in said first device and thereby causing the initiation of conduction in said second device.

4. In a rectifying circuit having two parallel branch paths through which currents are transmitted from an alternating-current source to a load, said paths respectively comprising a first and a second gaseous space current rectifying device each having an anode, a cathode and a control electrode, means for insuring substantially equal division of current in said rectifying devices comprising an inductance device having a first and a second winding, means for connecting different portions of said first winding respectively between the anodes of said rectifying devices and the said alternating-current source, a source of direct-current biasing voltage, a circuit connecting the control electrode and cathode of said second rectifying device including said second winding and said source of biasing voltage, and a circuit connecting the control electrode and cathode of said first rectifying device including said source of biasing voltage and a source of voltage for causing conduction to be initiated in said first device and thereby causing the initiation of conduction in said second device.

5. In a rectifying circuit having two parallel branch paths through which currents are transmitted from an alternating-current source to a load, said paths respectively comprising a first and a second gaseous space current rectifying device each having an anode, a cathode and a control electrode, means for insuring substantially equal division of current in said rectifying devices comprising an inductance device having a first and a second winding, means for connecting a first portion of said first winding between the cathode of said first rectifying device and said load and a second portion of said first winding between the cathode of said second rectifying device and said load, a source of direct-current biasing voltage, a circuit connecting the control electrode and cathode of said second rectifying device including in series said second winding, said source of biasing voltage and said second portion of said first winding, and a circuit connecting the control electrode and cathode of said first rectifying device including in series said source of biasing voltage, said first portion of said first winding and a source of voltage for causing conduction to be initiated in said first device and thereby causing the initiation of conduction in said second device.

6. In a rectifying circuit having two parallel branch paths through which currents are transmitted from an alternating-current source to a load, said paths respectively comprising a first and a second gaseous space current rectifying device each having an anode, a cathode and a control electrode, means for insuring substantially equal division of current in said rectifying devices comprising a center-tapped inductance coil, means for connecting one half of said coil between the cathode of said first rectifying device and the said load and the second half of said

coil between the cathode of said second rectifying device and the said load, a source of direct-current biasing voltage, a circuit connecting the control electrode and cathode of said second rectifying device including said source of biasing voltage and said second half of said coil, and a circuit connecting the control grid and cathode of said first rectifying device including the first half of said coil, the said source of biasing voltage and a source of voltage for causing conduction to be initiated in said first device and thereby causing the initiation of conduction in said second device.

7. In a rectifying circuit having two parallel branch paths through which currents are transmitted from an alternating-current source to a load, said paths respectively comprising a first and a second gaseous space current rectifying device each having an anode, a cathode and a control electrode, means for insuring substantially equal division of current in said rectifying devices comprising an inductance device having a center-tapped first winding and a second winding, means for connecting the two halves of said first winding respectively in the said parallel branch paths, a source of direct-current biasing voltage, a circuit connecting the control electrode and cathode of said second rectifying device including said source of biasing voltage and said second winding, and a circuit connecting the control electrode and cathode of said first rectifying device including said source of biasing voltage and a source of voltage for causing conduction to be initiated in said first device and thereby causing the initiation of conduction in said second device.

8. In combination, a first and a second gaseous space current device each having an anode, a cathode and a control electrode, means for supplying current from an alternating-current source to a load through a circuit having two parallel branch paths, an inductance device having a first and a second winding, means for connecting said windings in said branch paths respectively between a first terminal of said load and said cathodes respectively, control circuits including said windings respectively for connecting the control electrode and cathode of said space current devices respectively, and means for impressing an alternating voltage upon one only of said control circuits to cause conduction to be initiated repeatedly and substantially simultaneously in both said space current devices.
